MACHINE FOR APPLYING REINFORCING
CANVAS TO INSOLES

John A. Scott, St. Louis, Mo.

Application November 9, 1931. Serial No. 573,742

25 Claims. (Cl. 12—20)

This invention relates generally to shoe machinery and more particularly to machines for applying reinforcing material to the insole of a shoe.

5 Heretofore in the manufacture of shoes, the reinforcing member which generally consists of a canvas strip was first cut to proper length, then applied manually to the insole by means of suitable cement. The canvas strip is then secured to the channel of the insole and is trimmed so that the edge thereof is flush with the edge of the channel.

10 The primary objects of the present invention are to provide a machine which automatically cuts off the required length of canvas and secures it by suitable cement to the insole as the latter is fed through the machine so that the operation can be performed quickly and efficiently without the use of manual labor.

15 20 Other objects of the invention are to provide a machine having means for feeding an insole therethrough and provided with mechanism which cuts a strip of canvas into the particular length required by the size of the insole, or rather 25 by the channel portion thereof, there being means provided for applying a suitable cement to one side of said canvas whereupon the latter is brought under pressure into contact with the insole so that when the latter is automatically discharged from said machine, the reinforcing canvas is securely attached to said insole.

25 30 Still other objects of the invention are to provide an automatic machine of the class described having means for feeding a strip of canvas to a mechanism which cuts it into the desired length, said mechanism being controlled by the channel formed on the insole so that the length of the canvas corresponds to the length of the channel portion.

35 40 Further objects of my invention are to provide an automatic machine for applying reinforcing material to insoles, said machines having means for pressing the severed strip against the insole during the travel of the latter through said machine.

45 50 Still further objects of the invention are to provide feeding means for a machine of the class described, said feeding means being operable to engage one end of the insole and move the latter forwardly through the machine until said insole is engaged by the presser rollers which force the canvas against the channeled side of said insole and discharge the latter from the machine.

55 Additional objects of the invention are to provide a machine of the class described which is

automatic in operation, which is of simple construction, and highly efficient in operation.

With these and other objects in view, my invention consists in certain novel features of construction and arrangement of parts, hereinafter more fully described and claimed, and illustrated in the accompanying drawings, in which—

clutch member and means for actuating the same and showing the driven feed roller in released position.

Figure 21 is a top plan view of the clutching mechanism with the clutch members interengaged.

Figure 22 is a view similar to Figure 20 but showing the actuating means in clutch disengaging position and the driven feed roller locked in moved position.

Figure 23 is a horizontal detail cross section taken on line 23-23 of Figure 22 and showing the clutch members in disengaged relationship.

The present invention relates to a machine for applying a strip of canvas or other reenforcing material A to the channeled face of inner sole B and to the channel C thereof. Heretofore, such operations have been performed manually and required considerable time.

Briefly described, in my machine a required length of the reenforcing material is automatically severed from a roll of material and the severed section is moved downwardly into the machine whereupon a suitable cement is applied to one side thereof. The strip is then placed under pressure to the channeled side of the inner sole, which latter is automatically moved through said machine. As it is desired to reinforce only the channeled length of the sole, the feeding and cutting of the strip of the reenforcing material is regulated by the upstanding channel portion of the inner sole.

Referring by numerals to the accompanying drawings, 10 indicates a supporting frame including uprights 11 and a plurality of longitudinally and horizontally disposed bars 12. The latter are arranged in spaced relation on each side of the machine and are secured at their ends to the respective uprights.

40 A bearing block 14 is arranged on each side of the machine between the uppermost bar 12a and the next bar 12b. Each bar is held in position, preferably by a set screw 15. A horizontally and transversely disposed shaft 16 is revolutely mounted in said blocks. One end of this shaft has fixed thereon a pulley 17 over which operates a belt 18 connected to an electric motor or other suitable prime mover. While this is the preferred form of driving connection, other driving arrangement can be used between the motor and the shaft 16. The other end of said shaft has fixed thereto a sprocket wheel 19 over which operates a sprocket chain 20. This chain is engaged by a comparatively large sprocket wheel 21 which is operatively associated with a shaft 22 in the manner hereinafter more fully described (see Figures 1 and 2).

This shaft is journaled in a pair of bearing blocks 24, each of which is mounted between a pair of spaced bars 12c and 12d and is held in position by a set screw 24a. The other end of shaft 22 has fixed thereon a sprocket wheel 25 over which operates a sprocket chain 26. A sprocket wheel 27 is fixed to the corresponding end of a shaft 28 and said chain 26 engages said wheel, thereby operatively connecting shafts 22 and 28.

70 The latter has bearings in blocks 29 which are slidably mounted between bars 12a and 12b substantially in a vertical plane with shaft 22 and its bearing blocks 24. A feed roller 30 is fixed on shaft 28 and cooperates with a feed roller 31 which is fixed on a shaft 32. Bearing blocks 34 are fixed between the respective bars 12a and 12b in spaced relation with bearing blocks 29 and

14 and form bearings for shaft 32. These bearing blocks are preferably held in fixed position by set screws 34a.

Thus the feed roller 30 is driven by shaft 16 through the sprocket wheels and chain 19, 21, and 20, respectively, which in turn operate shaft 22 and sprocket wheel 25, chain 26, and sprocket wheel 27, the latter being carried by shaft 28 which also carries the movable feed roller 30. When the latter is moved toward feed roller 31, said feed rollers cooperate to engage the strip of canvas A and move it downwardly, as indicated in Figure 19. A roll of this canvas is mounted by means of a rod 38 in brackets 39 and the latter are preferably carried by the forward uprights 11, as shown in Figure 3.

Located immediately below the feed rollers 30 and 31 is the severing mechanism 39 which comprises a fixed blade 40 and a movable blade 41. These blades are disposed horizontally and transversely of the machine and the strip of canvas is fed between said blades as shown in Figure 3. Blade 40 is mounted on a block 42 which is fixed between bars 12b and 12c below movable feed roller 30. Movable blade 41 is carried by a block 44 which is slidably mounted between said bars below feed roller 31. Thus the canvas strip after it leaves the feed rollers is cut into the required lengths by said blades.

The actuation of the slideable block 44 is effected by a pair of eccentrics 45 which are fixed to a shaft 46 and operate within eccentric straps 47 secured to and extending forwardly from said slideable block 44. These straps are so shaped as to provide clearance for the movement of the eccentrics in vertical planes so that the block is actuated in a horizontal plane only.

Shaft 46 has bearings in blocks 48 which are fixed between bars 12b and 12c. The righthand end of said shaft has fixed thereto a large gear 49 which meshes with a small gear 50 fixed to shaft 16. Thus the actuation of the eccentric shaft 46 and the movable blade 41 is obtained from the drive shaft 16.

Large gear 49 is mutilated, as shown at 49a (Figs. 11 and 12). This mutilated portion is of sufficient size to prevent said gear from being engaged by gear 50 when in the position shown in Figure 11. Thus while gear 50 is constantly operated, gear 49 and shaft 46 and parts associated therewith are operated intermittently and are rendered stationary at the end of each revolution. The purpose of this arrangement is to operate the movable blade at regular intervals so as to cut the canvas strip into desired lengths and in predetermined time relation with the movement of the inner sole through the machine.

It is important to cease the feeding operation of the canvas strip to the machine the moment said strip is cut. To accomplish this, feed roller 30 is mounted for movement in a horizontal plane, bearing blocks 29 being slidably mounted in the respective bars. Each of said blocks is provided with an outwardly projecting lug 29a having a vertically disposed face presented toward shaft 46. Slidable block 44 has fixed to each end a finger 51 which projects toward the respective lug 29a. The end 51a of each finger terminates adjacent to the vertical face of the lug. When said slideable block 44 is actuated into home position, each finger 51 engages the respective lug, thereby causing blocks 29 and roller 30 carried thereby to move away from feed roller 31. As the roller 30 is positively driven (see Fig. 163), it is obvious that the feed roller 31 will be ren-

- dered stationary as soon as the roller 30 is moved out of engagement therewith, thereby producing stoppage of the canvas strip. As soon as the feed roller 30 and blocks 29 are moved rearwardly 5 a suitable distance, the upwardly presented hooks 52 formed on the ends of horizontal arms of bell cranks 54 engage said lugs 29 and hold said blocks and roller in retracted position, as shown in Figure 16.
- 10 Each bell crank 54 is pivotally mounted at 55 on the outer side of bar 12b and has its depending arm 54a extending rearwardly of and below an eccentric 56. A coiled spring 57 engages each bell crank and tends to hold the arm 54a against the eccentric and the hook 52 against the lug 29. The eccentrics 56 are fixed to the projecting ends of a shaft 58 which latter is revolvably mounted in bearing blocks 59. One end of shaft 58 has fixed thereon a sprocket wheel 60 and operating over this sprocket wheel is a sprocket chain 61, which latter also engage a sprocket wheel 62 fixed to the corresponding end of shaft 46. Thus shafts 46 and 58 are operatively interengaged and the large gear 49 is imparted slight 20 revolvable movement so as to bring it into operative engagement with gear 50 when said shaft 58 is actuated in a manner hereinafter described.
- The canvas A after passing between blades 40 and 41 is engaged by a pair of rollers 64 and 65. 30 Roller 64 is fixed to shaft 22 and roller 65 is fixed to a shaft 66 which latter is journaled in bearing blocks 67 forwardly of shaft 22. Each of said blocks is slidably mounted between bars 12c and 12d in spaced relation with blocks 24 of shaft 22. A horizontally disposed screw 68 is screw-threaded in a block 69 and bears against each block 67, thereby holding the roller 65 in fixed relation with roller 64. Blocks 69 are held stationary by set screws 70 which engage bars 12c and said blocks. Thus by adjusting set screws 68 the clearance between rollers 64 and 65 can be regulated in accordance with the thickness of the canvas strip to insure proper operative relationship there-between.
- 45 Roller 64 is coated with a rubber cement or other suitable adhesive and as said canvas strip passes between said rollers that side of the strip contacting with the roller 64 consequently receives a coat of cement.
- 50 The cement is applied to roller 64 by a roller 71 with which said first-mentioned roller is in peripheral contact. Cement roller 71 is carried by a shaft 72 which is journaled in bearing blocks 74. The latter are mounted between bars 12c and 12d rearwardly of blocks 24 and are engaged by horizontally disposed screws 75. These are screw-threaded in blocks 76 and serve to maintain cement roller 71 in operating contact with roller 64. Blocks 76 are held stationary by suitable set screw 77.
- 55 The lower portion of roller 71 traverses a pan 78 which is horizontally disposed between bars 12b and is filled with cement. Thus as the roller 71 is actuated it picks up a certain amount of cement and transfers it to roller 64 which in turn applies it to the strip.
- 60 Rollers 64, 65 and 71 operate in unison as they are interengaged by gears 79, 80 and 81 which are fixed, respectively, to the lefthand ends of shafts 22, 66 and 72 (see Figs. 6 and 16). As stated before, shaft 22 is actuated from shaft 16 through the medium of sprocket wheels 19 and 22 and sprocket chain 20. The teeth of the respective gears are of sufficient depths to permit slight adjusting movements of rollers 65 and 65 relatively to rollers 64 without interrupting the operative connections of said gears.
- 65 Disposed below roller 65 is a pair of rollers 82 and 84 carried by shafts 85 and 86, respectively. These rollers are arranged in vertical plane with each other and their point of peripheral contact is arranged in substantially horizontal plane with table 87, roller 84 being located below said table and roller 82 thereabove. Disposed rearwardly of this pair of rollers and substantially below the forward end of pan 78 is a pair of rollers 88 and 89 carried, respectively, by shafts 90 and 91, roller 89 being disposed in horizontal plane with roller 84 while roller 88 being disposed in horizontal plane with roller 82.
- 70 Shafts 86 and 91 are revolvably mounted in bearing plates 92 which latter are disposed between and supported by the respective bars 12d and 12e. Shafts 85 and 90 are journaled in bearing blocks 94 which are mounted in plates 92 for movement in vertical planes. A coiled spring 95 is disposed above each bearing block 94 and the lower end of said spring bears against the respective bearing block while the upper end of the spring is engaged by the bearing plate 92, thereby yieldably holding rollers 82 and 88 against the respective rollers 84 and 89.
- 75 Rollers 82 and 88 which bear upon the channeled face of the insole are preferably formed in short sections, having knurled peripheral surfaces, spaced from each other, as shown in Figure 7. This is for the purpose of permitting said rollers to fit in the narrowest part of the channel portion of said insole so as to insure at all times proper operative engagement of the respective pairs of rollers.
- 80 In order to prevent the strip from sticking to any of the rollers and in order to insure at all times downward movement of said strips, roller 64 is provided with a plurality of peripheral grooves 64a which are traversed by guides 96. The upper ends of these guides are secured to bars 97 and the lower ends of said guides terminate a suitable distance above the table 87. Similarly roller 65 is provided with peripheral grooves 65a for receiving guides 98. The lower end of each guide passes under shaft 85 between the sections of roller 82 and then upwardly and is fixed to a rod 99. The upper end of each guide 98 is curved and terminates within the respective groove 65a away from roller 64. These guides eliminate all danger of the strip of canvas sticking to any of the rollers over which it passes. This precaution is especially desirable in the case of roller 64 which applies the cement to the canvas.
- 85 Shafts 86 and 91 are driven by a sprocket chain 100 which passes over a sprocket wheel 101 fixed to shaft 22 (see Figures 2 and 16). This sprocket chain engages sprocket wheels 102 and 103 fixed to ends of shafts 86 and 91, respectively. Shaft 85 has fixed to one of its ends a gear 104 which meshes with a gear 105 fixed on shaft 86, and shaft 90 has fixed thereon a gear 107 which meshes with a gear 108 fixed to one end of shaft 91. Thus the cooperating rollers 88 and 89 and cooperating pair of rollers 82 and 84 are positively driven by means of shaft 22.
- 90 Shafts 86 and 91 are disposed below table 87 and rollers 84 and 89 project slightly thereabove. The rear end 87a of said table extends a suitable distance from the machine, and operating over said table in a direction indicated by arrow are endless chains 109 arranged adjacent to each side of said table. These chains pass over sprocket

wheels 110 fixed to shaft 91 and over sprocket wheels 111 fixed to a shaft 112 mounted adjacent to the rear end of said table 87a. Preferably this shaft 112 is mounted in brackets 114 which are 5 fixed to said table and extend therefrom and said shaft is adjustable in said brackets so as to maintain the sprocket chain in proper taut relation.

A plurality of transversely disposed bars 115 are fixed to and extend between said chains and 10 operate over the top of the rear portion 87a. These bars are spaced a sufficient distance from each other so as to receive therebetween an insole which is placed on said table 87a. This insole is placed with the heel portion presented forwardly (see Fig. 7) and the toe portion of said insole is adapted to be engaged by said bar 115 so that as 15 said chains move forwardly over said table 87a, said insole is fed forwardly until the heel portion of said insole is engaged by rollers 88 and 89. Preferably the machine is built to operate upon two insoles simultaneously and in such 20 case the table 87a is provided with a medially and longitudinally disposed rib 117 which spaces the insoles from each other and forms a guide 25 therefor during the forward movements thereof. Bars 115 ride upon the surface of the table 87a and the central portion of said bar is formed arcuate, as indicated at 116, in order to clear rib 117 and also to set in operation at the proper moment 30 mechanism hereinafter described.

Each insole B is provided with an upstanding channel portion C. This channel portion is spaced from the edge of the insole and terminates short of the heel portion D thereof, thereby providing two upwardly and forwardly presented ends E. The rear end or toe portion F of the channel portion is spaced from the toe portion G of the insole. The insoles are placed on the rear table portion 87a, as shown in Figure 7, with 35 their channel portions presented upwardly and the heel portions D presented forwardly. The toe end F of the insole is engaged by the transverse bar 115, as the latter is moved forwardly by sprocket chains 109. During this movement 40 of the insole B forwardly or toward the machine, the heel portion D passes under shaft 58. The forward ends E of the channel portion engage a rib or blade 118 which is fixed to and projects radially and downwardly from said shaft (see 45 Figs. 13 and 16). The continued forward movement of the insole forces blade 118 forwardly, thereby causing partial rotation of shaft 58 so that the latter assumes position shown in Figure 50 14.

Normally or when the shaft 58 occupies home position (see Fig. 13) the eccentric 56 is presented upwardly and the bell crank 54 occupies locked position holding the feed roller 30 in disengaged 55 position (see Fig. 16); thereby preventing feeding of the canvas A into the machine.

When shaft 58 is partially rotated, as just described, the eccentric 56 is moved substantially into a position shown in Figure 14 in which position it actuates bell crank 54 so as to cause it to 60 release feed roller 30 and permit the movement thereof into cooperative engagement with the feed roller 31 by virtue of a coiled spring 30a which bears against block 29 and has one end anchored in a stationary block 29a (see Fig. 3).

70 Thus it will be noticed that the feeding movement of the canvas strip A is controlled by the entrance of the insole B into the machine and that no feeding movement of the canvas strip can be obtained if there is no insole present in 75 the machine.

The severing mechanism is so placed with respect to shaft 58 and the table 87 and the movements of the canvas strip and the insole are so interrelated that the forward end of the strip A engages the insole B at or near the forward ends 80 E of the channel portion C. Thus only the channeled portion of the insole has the canvas section applied to it.

Not only is the feeding movement of the strip 85 timed and controlled in accordance with the movement of the insole but the severing operation is also so interrelated that the end or toe portion G of said channeled portion controls the severing operation so that the length of the canvas strip is substantially equal to the length of the channeled portion regardless of any variations in the length of the latter. This automatic control of the severing operation is obtained by operating shaft 58 by the toe portion G of the channeled portion so as to effect driving engagement 90 between the mutilated gear 49 and pinion 50. To this end shaft 58 has fixed thereto intermediate its ends and in spaced relation with blade 118 a radially projecting pin 119. When the shaft 58 occupies normal position shown in 100 Figure 13, said pin 119 is disposed substantially in a horizontal plane and is presented rearwardly. After the shaft is initially actuated by the interengagement of the ends E of the channeled portion with the blade 118, said pin 119 occupies position 105 which is substantially vertical as shown in Figure 14. The length of this pin is such that it is not effected by the channeled portion C of the insole. When the toe portion F during the forward movement of the insole passes under shaft 110 58, the raised central portion 116 of bar 115 engages said pin 119 and moves it forwardly, thereby causing second partial rotation of shaft 58 and moving it into position shown in Figure 15. This second actuation of shaft 58 moves the mutilated portion of gear 49 relatively to pinion 50 so that the latter is brought into engagement with the teeth of gear 49, thereby setting in operation shaft 46 and the parts associated therewith which include the severing mechanism for 115 severing the strip and the feed roller disabling mechanism whereby the feeding movement of the strip is stopped in time relationship with the cutting operation.

This actuation of shaft 46 operates through chain 61 and sprocket wheels 60 and 62 shaft 58, thereby returning it to its normal position shown in Figure 13. When in this position the mechanism is rendered stationary by virtue of the mutilated portion 49a of the gear 49 being brought 120 adjacent to the pinion 50, as shown in Figure 11.

It is desirable to render the strip engaging rollers stationary during the cutting operation. This is especially true of rollers 64 and 65 which are located below the cutting mechanism and are used to apply a coat of cement to one side of the strip and feed the latter toward the table 87. To this end a clutch 120 is provided. This clutch consists of a driving member 121 and a driven member 122. This driving member 121 is conjoined to or formed integral with gear 21, which latter is loosely disposed on shaft 22. Driven member 122 is slidably arranged on said shaft and has non-rotative engagement therewith. A coiled spring 124 is arranged between driven member 122 and the corresponding bearing block 24 and yieldably holds the clutch members interengaged. One of the members 51 is provided with a laterally and rearwardly projecting arm 125 51b which has an inclined obliquely disposed face 150

125. This inclined face is adapted to engage a collar 126 formed on said driven member so that when member 44 is moved forwardly to bring the cutting blade 41 into engagement with the stationary blade 40, arm 51b by means of its face 125 causes driven member 122 to move against the influence of spring 124 out of engagement with the drying member 121, thereby stopping the actuation of the rollers and particularly rollers 64 and 65 immediately before and during the cutting operation. When this operation is completed and the movable blade 41 is retracted, arm 51b is also moved away from shaft 22, thereby permitting the clutch members 121 and 122 to enter into operative relation and continue the operation of rollers 64 and 65 as well as the rollers disposed therebelow and the chains 109. As the feed roller 30 has been moved away from feed roller 31 and locking in moved position during the forward movement of member 44, said feed rollers 30 and 31 are not rendered operative upon the return movement of member 44 and blade 41. During this interval while the rollers 64 and 65 and parts associated therewith are rendered stationary, gear 49 and shaft 58 due to their engagement with pinion 50, continue to operate. The synchronism of the operation of the various parts is not effected by the continuous operation of shaft 58 and gear 49 with respect to the strip engaging rollers since gear 49 is comparatively large and allowance is made thereby for the stoppage of the strip feeding mechanism.
- After passing between rollers 82 and 84 the insole B with the canvas strip attached thereto is discharged from the machine and the insole and the strip can be operated upon in the usual manner to trim and finish said strip. Pressure roller 82 is spring-pressed against roller 84 and applies pressure to the canvas strip so as to secure to the insole along the longitudinal lines. This roller is yieldably mounted and rides over the toe portion G of the channel portion C. There are several bars 115 attached to chains 109 and spaced suitable distances from each other so as to receive insoles of maximum sizes.
- The length of the canvas strip is automatically controlled by the length of the channeled portion C. Therefore it is not necessary to make any adjustments or changes for each different size of insoles and the latter can feed indiscriminately to the machine without any regard to the size.
- The machine is entirely automatic in regard to its various functions and so long as no insole is introduced into the machine no action, such as cutting, feeding the strip, or applying the cement, can take place even if the driving mechanism is actuated and chains 109 operated. Thus no waste of material takes place and on the other hand the machine is always ready to function.
- My machine is accurate in operation, can be actuated at a fair rate of speed thereby affecting a considerable saving in time and labor over the method now in use, and is entirely automatic in its action, and inexpensive to operate and maintain.
- While I have shown and described herein the preferred form of my invention, it is to be understood that various changes in the construction and arrangement of parts of my machine can be made and substituted for those herein disclosed without departing from the spirit of my invention.
- I claim:
1. In a machine of the class described, the combination of means for moving a channeled insole
- through said machine, a feeding means for feeding a strip of canvas, cutting means for severing said strip into sections, said cutting means being controlled by the channeled portion of said insole to cut said sections into predetermined lengths with respect to the length of said channeled portion, means for applying adhesive to one side of the severed section, and pressure means for applying said canvas section to the channeled face of said inner sole. 80
2. In a machine for applying reenforcing strip material to the channeled face of an insole, the combination of a strip feeding means, cutting means for severing said strip into sections of predetermined lengths, mechanism for actuating said cutting means and disconnecting said feeding means in correlation with each other, a pair of rollers for receiving said severed section, one of said rollers being supplied with a suitable adhesive for applying it to one side of said severed section, and an inner sole feeding means adapted to receive said severed section and applying it under pressure to the inner sole with the adhesive face of said section to the channeled face of said inner sole. 85
3. A machine for applying a reenforcing strip of canvas to insoles comprising in combination means for feeding a strip of canvas, means for cutting said strip into sections of predetermined lengths, intermittent driving mechanism for operating said cutting means and simultaneously with the cutting operation disconnecting said feed means, means for applying adhesive to one face of said severed section, and means for receiving an inner sole and said strip section and applying the adhesive side of said section to the channeled face of said inner sole. 90
4. A machine for applying a reenforcing strip of canvas to the channeled face of an insole comprising in combination means for feeding a strip of canvas, means for cutting said strip into sections of predetermined lengths, driving means for intermittently operating said cutting means and disconnecting said feed means immediately before the cutting operation, means for applying adhesive to one face of said severed section, means for receiving an inner sole and said section and applying the adhesive side of said section to the channeled face of said inner sole, and actuating mechanism for operating all of said means. 95
5. A machine of the class described comprising in combination means for feeding a strip of canvas, means for cutting said strip into sections of predetermined lengths, means for applying adhesive to one face of said section, means for feeding an inner sole and applying under pressure the adhesive face of said section to the channeled face of said inner sole, driving mechanism for actuating all of said means, and a member associated with said cutting means for disabling said feeding means in time relationship with the cutting operation of said cutting means. 100
6. A machine of the class described comprising in combination means for feeding a strip of canvas, means for cutting said strip into sections of predetermined lengths, means for moving an inner sole having a channeled portion on one face and for applying said section of canvas under pressure to said channeled face, and driving mechanism for positively actuating said inner sole feeding means and intermittently actuating said strip feeding means and said cutting means, said driving mechanism cooperating with the channeled portion of said insole whereby said cut- 105

ting means is operated to form strips of canvas in accordance with the length of said intermittent motion.

7. A machine of the class described comprising a pair of cooperating feed rollers for feeding a strip of canvas to the machine, means for cutting said strip into sections of predetermined lengths, means for feeding an inner sole to the machine and receiving the severed canvas section and applying it under pressure to the channeled face of said inner sole, driving mechanism for operating said means and one of said feed rollers, and means associated with said cutting means and operable in conjunction therewith to disengage said driven feed roller and stop the feeding movement of said strip in time relationship with the cutting operation.

8. A machine of the class described comprising in combination a pair of cooperating feed rollers for feeding a strip of canvas to the machine, one of said feed rollers being positively driven, means for cutting said strip into sections of predetermined lengths, means for feeding an inner sole through the machine and applying the severed canvas section under pressure to the channeled face of said inner sole, and a member operable in correlation with said feeding means for moving said driven roller out of engagement with the other roller and stopping the feeding movement in time relationship with said cutting operation.

9. In a machine of the class described, the combination with a canvas strip feeding means and a cutting means for severing said strip into sections of predetermined lengths, of a driving mechanism for operating said feeding means and said cutting means, and means operatively associated with said cutting means and operable by the channeled portion of an insole to disable said feeding means immediately before the cutting of said strip.

10. In a machine of the class described, the combination of a pair of cooperating rollers for feeding a strip of canvas to the machine, one of said rollers being positively driven and mounted for movement laterally relatively to the other roller, cutting means operable to cut said strip into sections of predetermined lengths, mechanism for displacing said movable roller simultaneously with the cutting operation whereby said strip is rendered stationary during the same, means for moving said severed section away from said cutting means, and pressure rollers operable to apply said canvas section to an inner sole and discharge them from the machine.

11. In a machine of the class described, the combination of a pair of cooperating rollers for feeding a strip of canvas to the machine, one of said rollers being positively driven and mounted for movement away from the other roller whereby the latter and said strip of canvas are rendered stationary, cutting means operable to cut said strip into sections of predetermined lengths, mechanism operable in conjunction with the movement of the insole through said machine for operating said cutting means in time relation with the movement of said insole and in accordance with the length of the channeled portion thereof and for displacing said movable roller immediately before said cutting operation, a pair of cooperating rollers arranged below said cutting means for engaging the severed section of said strip, one of said last-mentioned rollers being supplied with adhesive for applying it to one side of said canvas, and pressure rollers disposed below

the last-mentioned rollers and operable to apply said canvas section to an inner sole with the adhesive coated side of said section placed against the channeled side of said inner sole.

12. In a machine of the class described, the combination of a pair of cooperating rollers for feeding a strip of canvas to the machine, one of said rollers being positively driven, cutting means operable to cut said strip into sections of predetermined lengths, a pair of cooperating rollers arranged below said cutting means for engaging the severed section of said strip, one of said last-mentioned rollers being supplied with adhesive for applying it to one side of said canvas, pressure rollers disposed below the last-mentioned rollers and operable to apply said canvas section to an inner sole with the adhesive coated side of said section placed against the channeled side of said inner sole, driving mechanism for actuating said rollers and said cutting means, and a member associated with said cutting means and operable in conjunction therewith for disabling said strip feeding means and disconnecting said driving mechanism from said adhesive applying rollers and said pressure rollers.

13. In a machine for applying a reinforcing strip of canvas to the channeled portion of an insole, the combination with a canvas strip feeding means and a cutting means for severing said strip into sections of predetermined lengths, of a driving mechanism for operating said feeding means and said cutting means, a means operatively associated with said cutting means and controlled by said channeled portion to disable said feeding means in time relationship with the operation of said cutting means and a member for locking said feeding means in disabled position, operating said cutting means.

14. In a machine of the class described, the combination with a pair of cooperating rollers for feeding a canvas strip and a cutting means for severing said strip into sections of predetermined lengths, of a driving mechanism for operating one of said feed rollers and said feeding means, a member associated with said cutting means and operable to move said driven feed roller out of engagement with the other roller and interrupt the feed movement of said strip during the cutting operation, a member for locking said driven feed roller in disengaged position, and means operable by the movement of an inner sole through said machine for displacing said locking member and releasing said driven feed roller into operative position.

15. A machine for applying reinforcing canvas lining to an inner sole comprising in combination a pair of cooperating feed rollers for feeding a canvas strip to the machine, cutting means for cutting said strip into sections of predetermined lengths, a pair of rollers for moving the severed section away from said cutting means, a pair of pressure rollers for engaging an inner sole and said severed section of canvas and applying the latter to the channeled side of said inner sole, and a driving mechanism for positively actuating said feed and pressure rollers and intermittently operating said cutting means.

16. In a machine of the class described, the combination with a pair of cooperating feed rollers for feeding a strip of canvas, of means for driving one of said feed rollers, cutting means for cutting said strip into sections of predetermined lengths, and a member cooperatively associated with said cutting means and operable to engage said driven feed roller and move it out of engage-

- ment with the other roller to interrupt the feeding movement of said strip in predetermined time relation with the cutting operation, and a member for engaging said driven feed roller and locking it in inoperative position. 80
17. In a machine of the class described, the combination with a pair of cooperating feed rollers for feeding a strip of canvas, of means for driving one of said feed rollers, cutting means for cutting said strip into sections of predetermined lengths, a member cooperatively associated with said cutting means and operable to engage said driven feed roller and move it out of engagement with the other roller to interrupt the feeding movement of said strip in predetermined time relation with the cutting operation, a member for engaging said driven feed roller and locking it in inoperative position, and means controlled by the movement of an inner sole through said machine for displacing said locking member and permitting said feed roller to move into operative position. 85
18. In a machine for applying a reenforcing strip of canvas to the channeled face of an insole, the combination with a canvas feeding means and means for cutting said strip into sections, of an insole feeding means, and mechanism operable by said channeled portion of said insole and by said insole feeding means for controlling the operation of said canvas feeding means and said cutting means in time relationship with the movement of said insole, whereby the length of the severed section is controlled by the length of said channeled portion of said insole and said feeding means is rendered stationary during said cutting operation. 90
19. In a machine of the class described, the combination with a canvas strip feeding means, of means for locking said feeding means in inoperative position, an insole feeding means, a mechanism operable by a part of said insole for operating said locking means to release said feeding means whereby a strip of canvas is fed into said machine in predetermined time relationship with the feeding movement of said insole. 95
20. In a machine for applying reenforcing material to the channeled face of an insole, the combination of a canvas strip actuating means, insole feeding means, and a mechanism operatively associated with said insole feeding means and operable by the latter and the channeled portion of said insole for controlling the operation of said actuating means whereby the latter is operated in time relationship with the feeding movement of said insole. 100
21. In a machine of the class described, the combination of a canvas strip actuating means, cutting means for severing said strip into sections, insole feeding means, intermittent driving mechanism for said strip actuating means and said cutting means whereby said strip actuating means is rendered stationary after each cycle of operation and said cutting means is operated immediately after rendering said actuating means stationary, and a mechanism operatively associated with said insole feeding means and with the channeled portion of each insole for controlling the operation of said driving mechanism whereby said strip actuating means is operated in time relation with the feeding movement of said insole, and said cutting means operated in accordance with the length of the channeled portion of said insole. 105
22. In a machine of the class described, the combination of a canvas strip feeding means, means for locking said means in inoperative position, cutting means for severing said strip into sections, mechanism for operating said cutting means, mechanism for operating said locking means to release said feeding means, and means for feeding an insole to said machine, both of said mechanisms being operable in correlation with the feeding movement of said insole whereby said feeding means and said severing means are actuated in time relation therewith. 110
23. In a machine of the class described, the combination with a canvas strip feeding means, of means for cutting said strip into sections, a plurality of rollers for moving said severed section and applying it under pressure to one side of an insole, means for feeding an insole to said machine, driving connections for said rollers, and means operable in conjunction with said cutting means for disabling said driving mechanism and rendering said rollers and said strip stationary during the severing operation. 115
24. In a machine for applying reenforcing material to the channeled face of an insole, the combination of a canvas strip feeding means, a member for locking said feeding means in inoperative position, means for feeding to said machine an insole having a channeled portion, and a member operatively associated with said locking member and operable by the forward end of said channeled portion of said insole to actuate said locking member and release said feeding means whereby the canvas strip is fed into the machine in predetermined time relationship with the feeding movement of said insole. 120
25. In a machine for applying a reenforcing strip to the channeled face of an insole, the combination with a canvas strip feeding means, of cutting means for severing said strip into sections, a plurality of rollers for moving the severed section away from said cutting means, means for moving a channeled insole through said machine, driving connections for said cutting means and said plurality of rollers, said driving connections being normally inoperative, and a member operable by the channeled portion of said insole and operatively associated with said driving connection for rendering the latter operative to actuate said cutting means in accordance with the feeding movement of said insole through said machine and to render said rollers inoperative during said cutting operation. 125
